COMBINED WALL BRACKET AND FLOWER
HOLDER OR THE LIKE

Michael Iwanoski, Newark, N. J.

Application December 2, 1949, Serial No. 6,388

Term of patent 7 years

(Cl. D35—3)

To all whom it may concern:

Be it known that I, Michael Iwanoski, a citizen of the United States, residing at #720 South 15th Street, in the city of Newark, county of Essex, and State of New Jersey, have invented a new, original, and ornamental Design for Combined Wall Bracket and Flower Holder or the like, of which the following is a specification, reference being had to the accompanying drawing, forming a part thereof.

Fig. 1 is a front elevational view and Fig. 2 is a side elevational view of a combined wall bracket and flower holder or the like, showing my new design. The receptacle is symmetrical about a vertical axis.

I claim:

The ornamental design for a combined wall bracket and flower holder or the like, as shown and described.

MICHAEL IWANOSKI.
